[57] CLAIM

The ornamental design for an electrical contact pin, substantially as shown and described.

DESCRIPTION

FIG. 1 is a perspective view of an electrical contact pin showing the new design;

FIG. 2 is a side elevational view thereof;

FIG. 3 is a top plan view thereof;

FIG. 4 is a bottom plan view thereof;

FIG. 5 is an end view thereof, taken from the left side of FIG. 2;

FIG. 6 is an end view thereof, taken from the right side of FIG. 2; and

FIG. 7 is a fragmentary view thereof, taken in the direction of arrow 7 in FIG. 5, the contact pin being fragmentarily shown for convenience of illustration.
